UNITED STATES PATENT OFFICE.

WILLIAM A. SPARKS, OF CHARLESTON, WEST VIRGINIA, ASSIGNOR TO SPARKS DRILLING JAR COMPANY, OF CHARLESTON, WEST VIRGINIA, A CORPORATION OF WEST VIRGINIA.

METHOD OF MAKING WELL DRILL-JARS.

1,134,926.

Specification of Letters Patent.

Patented Apr. 6, 1915.

Application filed February 4, 1914. Serial No. 816,497.

To all whom it may concern:

Be it known that I, WILLIAM A. SPARKS, a citizen of the United States, residing at Charleston, in the county of Kanawha and State of West Virginia, have invented certain new and useful Improvements in Methods of Making Well Drill-Jars; and I do hereby declare the following to be a full, clear, and exact description of the invention, such as will enable others skilled in the art to which it appertains to make and use the same.

In oil well drilling, where it is usually necessary that a well be drilled through rock, it has been found desirable to employ drill jars which will permit of rotating movement of the parts as well as reciprocating action.

This invention relates to a method of making well drill jars without the employment of welding heat or the screw threading of the parts, the members of the jar being formed from solid pieces of metal so united that one jar member may rotate as well as reciprocate with relation to the other jar member.

A purpose of the invention is to reduce the the cost of manufacture of a set of drill jars, and produce well drill jars which will give a greater impact or "jar" for the size and weight of the material, than the commercial jars now in use, and especially the ordinary link jars; to produce jars in which the material retains its natural strength, not having been vitiated by welding heat, and thereby increase the durability of the product; to produce a jar, the members of which will be permanently connected; and to provide a set of jars of few parts which, if they become broken in a well, will result in an easy, inexpensive fishing operation to remove the broken parts from the partially drilled well.

One method of producing well drill jars of the type set forth, may now be stated and is illustrated in the accompanying drawings, in which:

Figure 1 is a side elevation, partly in section, illustrating one embodiment of the invention. Fig. 2 is a side elevation, partly in section, illustrating another embodiment of the invention. Fig. 3 is a vertical sectional view through a socket member of Fig. 1. Fig. 4 is a side elevation of a sectional re-

taining collar, the parts being shown separated. Fig. 5 is a bottom plan view of the collar showing the seat for the piston head. Fig. 6 is a vertical sectional view through a socket member of Fig. 2. Fig. 7 is a side elevation of a sectional retaining collar to be inserted into the socket member of Figs. 2 and 6. Fig. 8 is a top plan view of the sectional collar of Fig. 2.

In the manufacture of a set of drill jars of the type illustrated herein, the piston member 10 is made from a single solid piece of metal free from welds, which is placed in a suitable tool, such as a lathe, to produce a hammer portion 11, a shank 12, and a head 13, all the parts being integral. The shank 12 is illustrated as of less diameter than the hammer portion 11 to produce a shoulder 14. This shoulder 14 may be provided with a rounded non-battering lower edge 15, and the metal at the juncture of the hammer 11 and shank 12 may be rounded as at 16. It is preferred to elongate the head 13 and to incline or round the upper portion 17 where it joins the shank, and to round the lower face 18. All of these parts may be made in the usual or any preferred manner. The socket member 19 is also formed from a single solid piece of metal, bored to produce an elongated chamber 20 having its wall 21 of substantially the same thickness throughout, as shown in Fig. 3, although in Fig. 6 the upper end of the wall 21 is thickened as at 22. The chamber 20 may now be provided with a rounded lower end or seat 23 to substantially fit the rounded end 18 of the head, and connecting with this seat may be formed a drain duct 24 shown leading from the central portion of the seat 23 to more effectually clear the chamber 20 of foreign substances, and at the same time prevent any injurious effect or battering of the head. The upper end of the socket member 19 may now be bored out at 25 to increase the diameter of the chamber 20 at the upper end thereof, producing a shoulder 100 intermediate the ends of the chamber, and leaving the chamber 20 open at the upper end 27 of the socket member. However, this larger portion 25 may be bored, previous to boring the remainder of the chamber 20 which is of less diameter, in which event the shoulder will be formed, when the reduced diameter of the chamber is bored,

as a continuation of the first cut. The end 27 of member 19 may now be heated to an ordinary red heat, and the head 13 inserted into the chamber 20. A stop collar, shown comprising a plurality of sections 28-29, is now placed around the shank 12 of the piston and above the head 13, and this collar 28-29, is driven down into the widened portion 25 of the chamber 20 until the lower end 30 of the collar engages the shoulder 26 and is seated against the latter. The lower end 30 of this collar is preferably formed to receive and seat the rounded upper portion 17 of the head to produce a non-battering upper seat for the head, as shown in Fig. 5. The upper inner surface of the collar members 28-29, may be rounded out to correspond with the joint 16 of the piston member where the shank 12 is united to the hammer 11, to prevent battering of the metal.

If desired, the heated end 27 of the wall of the chamber 20 may be simply allowed to cool and contract around the collar 28-29, although it is preferred to contract the metal of the end 27 around the collar 28-29 and the shank 12, by a suitable tool, such as a hammer, to permanently secure the collar within the socket, and thereby lock the piston member to the socket member. Should the socket member become elongated by the heating and compressing operations, the parts may be placed in a suitable tool and the end 27 of the socket member 19 trimmed down until the end 18 of the head 13 engages its lower seat 23 at substantially the same time that the hammer portion 11 engages the end 27. This feature of the jar serves to relieve the strain on the head of the piston member, prevents the head from spreading or thickening, and also prevents the shank of the piston member from bending, buckling or expanding, when under compression and stress of the drilling operations. Moreover, the engagement of the cylindrical head with the walls of the chamber and the guiding action of the collar members 28-29 on the shank 12, operate to bring the head into register with its oppositely positioned seats 23, 30 within the chamber 20.

In Figs. 2, 6, 7 and 8, the socket member is provided with a thickened upper wall, as at 22, and the outer surface of the upper end of the collar members 28-29 is slightly cut away as at 31. The lower end of the collar of Fig. 7 is provided with a seat 30 for the head in the same manner as the collar illustrated in Fig. 4. In assembling the parts, the thickened part of the wall 22 may be heated and compressed around the tapered or cut away portion 31 of the collar 28-29, to the position shown in Fig. 2, thereby permanently securing the collar to the socket and permanently locking the piston member 65 to the socket member.

Having thus described the invention, what I claim as new and desire to secure by Letters Patent is:

1. The method of making well drill jars which consists of producing a hammer portion, shank and head of a piston member from a single solid piece of metal free from welds, boring an elongated chamber into another single solid piece of metal, boring a continuation of said chamber of less diameter than the first bored portion to leave a shoulder, heating the walls of the first named chamber, inserting the head of the piston member in the chamber of smaller diameter, placing a collar around the shank 70 of the piston member, and forcing the collar into the chamber of greater diameter until the end of the collar engages the shoulder.

2. The method of making well drill jars 85 which consists of producing a hammer portion, shank and head of a piston member from a single solid piece of metal free from welds, boring an elongated chamber into another single solid piece of metal, boring a 90 continuation of said chamber of less diameter than the first bored portion to leave a shoulder, heating the walls of the first named chamber, inserting the head of the piston member in the chamber of smaller diameter, placing a collar around the shank 95 of the piston member, forcing the collar into the chamber of greater diameter until the end of the collar engages the shoulder, and contracting the heated end of the chamber 100 member around the collar.

3. The method of making well drill jars which consists of producing a hammer portion, shank and the head of a piston member from a single solid piece of metal free from 105 welds forming non-battering faces on the piston head, boring a chamber into another single solid piece of metal, boring a continuation of said chamber of less diameter than the first bored portion to leave a shoulder between the portions of the chamber of different widths, forming a substantially cylindrical collar of a plurality of sections from another piece of metal, heating the upper end of the socket member, inserting the 110 head of the piston member into the chamber of smaller diameter, placing the sections of the collar around the shank of the piston member above the head, forcing the collar into the chamber of greater diameter until 115 one end of the collar engages the shoulder, and contracting the heated end of the chamber member around said collar, thereby locking the piston member into permanent engagement with the socket member.

4. The method of making well drill jars which consists of producing a piston member from a single solid piece of metal comprising a hammer portion, a shank and a head, forming non-battering faces on the 120

piston head, boring a chamber into another single solid piece of metal, and leaving a portion of the wall at the top of said chamber of greater thickness than an adjacent portion of said wall, boring a continuation of said chamber of less diameter than the first bored portion to leave a shoulder between the portions of the chamber of different widths, forming a substantially cylindrical collar of a plurality of sections from another piece of metal, cutting away a portion of the collar at the upper end thereof, heating the upper end of the socket member, inserting the head of the piston member into the chamber of smaller diameter, placing the sections of the collar around the shank of the piston member above the head, forcing the collar into the chamber of greater diameter until one end of the collar engages the shoulder, and contracting the heated end of the chamber member around said collar to compress the thickened portion of the wall at the top of the chamber against the cut away portion of the collar to prevent movement of the collar out of the chamber, thereby locking the piston member into permanent engagement with the socket member.

In testimony whereof, I affix my signature in presence of two witnesses.
